Patented Feb. 24, 1914.

UNITED STATES PATENT OFFICE.

JAMES E. POTTER, JR., OF BEAMAN, MISSOURI.

WIRE-STRETCHER.

1,088,621.

Specification of Letters Patent. Patented Feb. 24, 1914.

Application filed November 11, 1910. Serial No. 591,860.

To all whom it may concern:

Be it known that I, JAMES E. POTTER, Jr., a citizen of the United States, residing at Beaman, in the county of Pettis, State of Missouri, have invented certain new and useful Improvements in Wire-Stretchers; and I do hereby declare the following to be a full, clear, and exact description of the invention, such as will enable others skilled 10 in the art to which it appertains to make and use the same.

This invention relates to wire stretchers, and is particularly adapted for stretching fence wire of the woven type.

15 The object of the invention resides in the provision of a wire stretcher which can be easily and quickly secured to a fence post in a detachable manner, and which when so secured may be easily operated to stretch 20 the woven wire of the fence structure.

A further object of the invention resides 25 in so constructing the wire stretcher that same may be reversed in its position on the post so as to effect the stretching of the desired wire irrespective of the disposition of 30 the wire on one side of the post or the other.

With these and other objects in view, the invention consists in the details of construction and in the arrangement and combination 35 of parts, to be hereinafter more fully described and particularly pointed out in the appended claim.

In describing the invention in detail, reference will be had to the accompanying 40 drawings, wherein like characters of reference denote corresponding parts; and in which,

Figure 1 is a front elevation of a section 45 of a fence showing the invention associated with a terminal post thereof and operatively connected to the wire stretcher; Fig. 2, a plan view of a fragment of what is shown in Fig. 1; Fig. 3, an end view of the invention detached from the post and looking at the 50 end thereof disposed farthest from the post in Fig. 1.

Referring to the drawings, 10 and 11 indicate the terminal posts of a fence section and 55 12 the intermediate post. Detachably connected to the terminal post 11 is a wire stretcher, which comprises corresponding side members 13 and 14 connected together in parallel spaced relation by cross rods 15. Connecting the side members 13 and 14 at the inner edge of the latter are spaced bars 16 and 17. The ends of these bars 16 and

17 are extended beyond the side member 14 and have mounted thereon respectively slideable sleeves 18. Pivoted to each of the sleeves 18 are post engaging hooks 19, the 60 free ends of each of which are provided with a spear 20 for insertion in a post. When the wire stretcher is secured to a post, these hooks 19 are disposed in a substantially horizontal position. The sleeves 18 65 are held against disengagement from their respective bars 16 and 17 by means of cross pins 21, which extend transversely through one of the terminals of said bars respectively.

70 Journaled between the side members 13 and 14 is a shaft 22, the ends of which are extended so as to project beyond the outer faces of the side members 13 and 14 respectively. One of these projecting ends of the 75 shaft 22 is squared, as at 23, so as to permit the operating lever 24 to be detachably associated therewith. Fixed on the shaft 22 adjacent the outer face of the side member 14 is a ratchet wheel 25, while another 80 ratchet wheel 26 is fixed on the shaft 22 adjacent the outer face of the side member 13. Pivoted upon the outer face of the side member 14 for operative engagement with the ratchet wheel 25 is a pawl 27, while another 85 pawl 28 is pivoted on the outer face of the side member 13 for engagement with the ratchet wheel 26; this last named pawl is positioned on the opposite side of the shaft 23 from the pawl 27, so that only one of the 90 pawls 27 or 28 will be in operative engagement with its respective ratchet wheel during the operation of the device.

95 In the position in which the wire stretcher is illustrated in Figs. 1 and 3, the pawl 28 is shown out of engagement with its respective ratchet wheel, the pawl 27 in this instance serving to prevent backward rotation of the shaft 22. However, should the wire stretcher be reversed from the position shown 100 in Figs. 1 and 3, the pawl 27 will be moved by gravity out of engagement with the ratchet wheel 25, while the pawl 28 will enter into engagement with the ratchet wheel 26. Fixed upon the shaft 22 outwardly of 105 the ratchet wheel 26 is a chain wheel 29, which has formed in its periphery a series of communicating recesses 30 for the reception of the links of a chain 31. Disengagement of the links of the chain 31 from the recesses 110 30 is prevented by means of a roller 32, which overlies the periphery of the wheel 29 and is

supported by means of a bracket 33 attached to the outer face of the side member 13. Secured to one end of the chain 31 is a wire clamping member.

5 It will be noted that by the use of the wire stretcher constructed as herein shown and described that the stapling of the stretched wire can be effected on the fence post to which the stretcher is attached. This result is made possible by reason of the peculiar formation of the stretcher which results in the major portion of same to be disposed entirely free of the stapling face of the post.

10 What is claimed is:—

15 15 The combination with a wire stretcher in-

cluding a frame having a rod extension at one side, and axially rotatable stretching mechanism carried by the frame with its axis of rotation parallel to said rod extension, of post engaging means in which the 20 rod extension is slidably mounted for movement transversely of the plane of the fence to be stretched.

In testimony whereof, I affix my signature, in presence of two witnesses.

JAMES E. POTTER, JR.
